UNITED STATES PATENT OFFICE

HENRY A. OWEN, OF FOXBORO, MASSACHUSETTS, ASSIGNOR TO DAVIS & FURBER MACHINE COMPANY, OF NORTH ANDOVER, MASSACHUSETTS, A CORPORATION OF MASSACHUSETTS

SPINDLE RAIL LIFTING MECHANISM

Application filed April 10, 1930. Serial No. 443,015.

The invention relates to spinning machines, and more particularly to machines of this class having bolster or spindle rails which are movable to traverse the spindles relatively to a fixed ring rail. Such construction is very desirable having many advantages over the other types of construction. Chief among such advantages is the ability to maintain uniform spinning conditions at all times. Since the ring rail is stationary the distance between the traveler and the bite of the drawing rolls or the thread guide remains fixed, and inasmuch as the portion of yarn lying between these two points is the particular section of yarn that is being spun, and since this portion of yarn is invariable in length it follows that a uniform twist is produced.

In a moving spindle rail machine of the usual type of construction the builder motion acts to lower the spindle rails from their upper position when the bobbins are empty to their extreme low position when they have received the desired quantity of yarn. The rails must then be lifted by hand to their initial position to permit doffing. The weight of the rails, spindles and other parts which must be moved is very great and consequently requires considerable effort to raise by hand which prohibits the employment of women operators to care for such machines. Furthermore, such a condition definitely limits the length to which a suitable machine may be built. The present invention has for its general object to overcome this limitation by providing power driven means to raise the spindle rails.

The object of the invention is further to provide means which may be connected to a driven element on the machine to raise the spindle rails into doffing position.

A further object of the invention is to provide a spindle rail lifting mechanism which may be manually connected to a moving part of the machine and which will function automatically to disengage therefrom when the rail has reached its uppermost position.

The object of the invention is further to provide means to prevent the spindle rail

from dropping rapidly downward by its own weight after the lifting mechanism has been disengaged from its source of power and before the builder motion has been restored to its starting condition.

The object of the invention is further to provide means connectible to a driven element on the machine which acts to raise the spindles into doffing position and continues to hold them in such position while the lifting means remains connected to the driven element.

Other objects and features will more fully appear from the following description in connection with the accompanying drawings, and will be particularly pointed out in the claims.

In the drawings:

Fig. 1 is a partial side view of a spinning frame embodying the principles of the invention.

Fig. 2 is a transverse sectional view substantially on line 2—2 Fig. 3.

Fig. 3 is a sectional view taken substantially on the line 3—3 Fig. 2.

Fig. 4 is a detail view on an enlarged scale of the mechanism which functions to raise the spindle rail.

Fig. 5 illustrates a modified form of the mechanism illustrated in Fig. 4.

Fig. 6 is a horizontal section on line 6—6 Fig. 4 looking down.

The invention is herein shown as applied to a typical form of spinning frame in which the bolster or spindle rails are movable and are controlled by the builder motion to lay the yarn on the bobbins in a mass of the desired shape. Certain of the general features of the machine are shown somewhat diagrammatically. End frames 1 and 2 are provided which constitute the major supporting members for the mechanism. The spindles 3 are supported upon moving spindle rails 4 and 5 situated respectively at the sides of the machine. The two rails are desirably connected together by means of a plurality of transverse connectors 6 to which the rails are secured at their outer ends. The spindles are thus supported upon a rail which is guided upon vertically disposed guide rods 7 which are se-

cured at the top in the ring rails 8 and at their bottom are secured to longitudinal horizontal supports 9. The supports 9 are in turn supported in the end frames 1 and 2. The guide rods extend through suitable apertures in the end of each of the transverse connectors 6. Apertures are also formed in the spindle rails to register with the apertures in the transverse supports through which the rods 7 also pass.

10 A builder motion is provided which controls the movement of the spindle rails relatively to the ring rails to build up a mass of yarn on the bobbins. Such a builder motion comprises an arm 10 pivoted at one end on a stud 11 secured to the end frame 1. The other end of the arm is provided with a follower 12 which is engaged by a builder cam 13 which is driven in the customary manner from a moving part of the machine such as the draft roll 14 through a suitable train of gearing 15 which drives a vertical shaft 16 having a worm 17 on the lower end thereof meshing with a worm gear 18 fixed to the shaft 19 upon which the cam 13 is mounted. The lobes on the cam as they ride over the follower 12 cause the arm to move. The motion of the arm is transmitted to the spindle rails in any desirable manner preferably by means of a flexible connector such as the chain 20.

15 The manner in which the flexible connector 20 functions to lift the spindle rails will hereinafter be more fully described.

A suitable pick motion for imparting gain to the traverse is illustrated. This is accomplished by unwinding a drum 21 upon which the chain 20 is wound. The drum 21 is fixed to a shaft 22 rotatably mounted in a frame 23 on the outer end of the arm 10. A worm gear 24 is also secured to the shaft 22 and is driven by a worm 25 fixed to a horizontal shaft 26 mounted in the frame 23. The shaft 26 also has a ratchet wheel 27 secured thereto at its outer end. Mounted loosely on the shaft 26 adjacent the ratchet wheel is an actuator 28 upon which is mounted a pawl 29 situated in a plane to engage the ratchet wheel 27. Located in the path of the actuator 28 is a stop 30 secured in a fixed bracket in a manner to be vertically adjustable.

As the arm 10 moves downwardly the actuator 28 engages the stop and is rotated through a small arc which in turn rotates the ratchet wheel 27 by reason of the engagement 55 of the pawl 29 with the teeth thereof. The drum 20 is thus actuated through the worm 25 and its gear 24. On the up stroke of the arm 10 the actuator 28 falls by gravity until a shoulder 32 on the actuator engages a stop 33 and upon the following down stroke the ratchet is again moved through its predetermined arc.

The motion of the arm 10 may be transmitted to the ring rail in any desirable manner. 60 As herein illustrated the connecting chain 20

extends upwardly and partially around a drum 34 fixed upon a transverse shaft 35 which is rotatably mounted in bearings 37 and 38 secured to longitudinal supports 39 and 40 which in turn are fixed to the end frames 1 and 2. The end of the chain 20 is fastened to the drum 34 at 41. Adjacent the drum 34 is a similar drum 42 which has a chain 43 partially encircling it and attached thereto at 44. From the drum 42 the chain 43 passes over an idler pulley 45 which rotates on a supporting shaft 46 fixed to a girder 47 extending lengthwise of the machine and securely attached to a rigid part thereof such as the longitudinal supports 39 and 40. The chain 43 extends lengthwise of the machine for a short distance and is secured to a connecting member preferably a bar 48 extending substantially throughout the length of the machine by means of an eye bolt 49 or other suitable fastening.

Secured to the bar 48 at suitable intervals are a plurality of flexible supporting members 50 which pass over a series of direction pulleys 51 rotatably mounted on the girder 47. The supporting members 50 are secured at their lower ends to the transverse connectors 6 at 52.

At the opposite end of the transverse shaft 35 is secured a drum 53 similar to the drum 42 and having secured to it and passing part way around its periphery a chain 54 which passes over an idler pulley 55 rotatably mounted on a girder 56 similar to and situated at the opposite side of the machine from the girder 47. The chain 54 passes from the pulley 55 to a connecting bar 57 similar to and operating in the same manner as the bar 48. The bar 57 has secured thereto flexible supporting members 58 which pass over idler pulleys 59 and thence downwardly and are connected to the opposite ends of the transverse connectors 6. The movement of the traverse mechanism oscillates the shaft 35 by means of the chain 20 which results in raising and lowering the spindle rails through the various connecting members above described.

When the bobbins are filled the spindle rails are in their lowest position, and in order to permit doffing and to start the spinning operations upon a group of empty bobbins the spindle rails must be raised to their uppermost positions. This operation has hitherto been accomplished by rotating the shaft 45 by hand and then taking up the slack in the chain 20 by rotating by hand the ratchet mechanism on the builder motion.

Novel means are provided herein which function to raise the spindle rails by power into doffing position and hold them in such position until the machine has been adjusted to start the spinning operation upon another group of bobbins. In order to illustrate the broad principle involved a specific manner of accomplishing the desired result is herein

shown. As previously pointed out the former method of lifting the rail was to rotate the shaft 35 by hand. Power derived from a moving part of the machine is in the present 5 instance directly applied to rotate this shaft and thus lift the spindle rails.

The draft roll 14 is driven positively from the draft roll 60 which is connected to the main drive of the machine which is not 10 shown. The usual structure is employed to drive the roll 14 from the roll 60 and consists of a bevel gear 61 on the roll 60 meshing with a complementary gear 62 mounted on a transverse shaft 63 having upon its opposite 15 end a bevel gear 64 which meshes with a complementary gear 65 upon the draft roll 14 by means of which it is positively driven at the same speed as the roll 60.

A rotating element on the machine is utilized to derive power to raise the spindle rail. The machine must, therefore, be in operation during the rail lifting operation. After the spindles have accumulated the required 20 amount of yarn the operator without stopping

25 the frame throws into operation the rail lifting means which will hereinafter be more fully described which immediately causes the rail to start rising. Since the machine continues to spin the yarn a coarse spiral of yarn 30 will be laid over the surface of the yarn mass as the rails rise which is a normal procedure and is desirable for various reasons well known to those skilled in the art. When the rails have reached their doffing position the 35 rail lifting means is automatically thrown out of operation and by means to be herein-after described is held in its raised position. The machine is then stopped by the operator to permit the full bobbins to be doffed.

40 The transverse shaft 63 serves as a convenient point from which to drive power to lift the spindle rails. To accomplish this a bevel gear 66 is fixed to the shaft 63 and meshes with a complementary gear 67 upon the end 45 of a vertical shaft 68 mounted in a swinging bracket 69 which has an offset arm 70. The arm 70 has a horizontal aperture 71 therein through which the shaft 63 passes and in which it may rotate. A collar 72 on the shaft 50 serves to prevent longitudinal movement of the bracket along the shaft by confining the arm 70 between the collar and the hub of the gear 66. At the lower end of the shaft 68 is secured a worm 73 which may be caused to 55 mesh with a worm gear 74 on the shaft 35.

The lower end of the bracket 69 embraces the worm 73 to present a bearing 75 below the worm. Adjacent the bearing 75 is located a pin 76 upon which is pivoted a short 60 link 77, the free end of which is pivotally connected to an arm 78 rigidly secured to a shaft 79 which in turn is pivoted in a bracket 80 secured to the end frame 2. The shaft 79 extends through the bracket 80 to present a 65 short section of shaft to which is secured an

arm 81, the outer end of which is located in the path of an arm 82 fixed to the shaft 35. The link 77 and the arm 78 are so aligned that they constitute a toggle connection between the bracket 69 and the frame 2 which is operated by means of a hand lever 83 secured to the shaft 79.

In the full line position in Fig. 4 the toggle is acting to maintain the worm in mesh with its gear 74 at which time the hand lever 83 bears against the stop 84 to maintain the link 77 and the arm 78 in alignment or preferably with the axis of their pivotal connection 85 slightly above the center line extending between the axis of the shaft 79 and the pin 76 thus locking the bracket against movement due to pressure tending to separate the worm and gear when a load is applied to the gear. To disengage the worm from the gear the hand lever 83 is swung into the dotted line position shown in Fig. 4 which breaks the toggle and permits the bracket 69 to swing about the shaft 35 into the dotted position.

In order to prevent the spindle rails from 90 dropping downward by their own weight when the worm 73 is disengaged from its gear a ratchet wheel 86 is secured to the shaft 35. The ratchet wheel 86 is engaged by a pawl 87 pivoted upon the transverse support 40 which acts to prevent rotation of the shaft 35 to prevent downward movement of the spindle rails.

When the bobbins have received the desired quantity of yarn the spindles are in 100 their lowest position and the spindle rails must be raised to permit doffing. During the normal operation of the machine the worm 73 is disengaged from the gear 74. The operator therefore must first move the 105 hand lever 83 from the dotted line position shown in Fig. 4 into the full line position. The machine is then operated to rotate the shaft 35 through the worm 73 and gear 74 thus raising the spindle rails. The arm 82 also rotates with the shaft 35 and is so positioned thereon as to engage the arm 81 on the shaft 79 of the toggle mechanism and automatically break the toggle when the spindle 110 rails have reached their top position. The ratchet wheel 86 and the pawl 87 then cooperate to sustain the rails in this position.

After doffing, the machine must again be put in condition to start the spinning operation to fill a group of empty bobbins. This 115 may be done in various ways. A preferred procedure however is as follows. During the process of raising the spindle rails above described the chain connection 20 leading to the builder motion has been slackened. This 120 slack is taken up in the usual manner by rotating the shaft 26 carrying the worm 25 until the chain is tight and the follower 12 is bearing against the face of the cam 13. The cam at this time preferably has been brought 125 130

into a predetermined position where the follower is closely adjacent to but not at the high point of the lobe on the cam so that the initial movement of the cam will raise the spindle rails very slightly, and in doing so will rotate the shaft 35 a slight amount and thus relieve the pressure of the particular tooth of the ratchet which is engaging the pawl and permit the operator to throw the pawl entirely out of engagement with the ratchet wheel. Thus the builder motion is again permitted to control the movement of the spindle rails.

The cam 13 is brought in the predetermined position above referred to in any desired manner such as by manipulation of the main starting mechanism of the machine after the spindle rail has been lifted by power as described and held in such position by the pawl and ratchet 86 and 87. The operator can accomplish the desired result by quickly starting and stopping the machine several times. The chain connector 20 is then tightened as above described. The machine is then in condition to resume spinning.

A modified form of mechanism to raise the spindle rails by power is illustrated in Fig. 5. In this construction a bracket 88 is suspended from the shaft 35 in the same manner as the bracket 69 and has a vertical shaft 89 therein driven by the beveled gears 66 and 67 from the shaft 63. On the lower end of the shaft 89 is secured a worm 90 which may be moved into engagement with a mutilated gear 91 on the shaft 35. The worm 90 is meshed with the gear 91 by means of a toggle mechanism similar to that used in the mechanism illustrated in Fig. 4. A link 92 is pivoted on the bracket 88 at one end and at its other end to an arm 93 secured to a shaft 94 pivoted in a bracket 95 fixed to the end frame 2. A hand lever 96 is secured to the arm 93 and adapted to be swung into the full line position shown in Fig. 5 to straighten the toggle which results in causing the worm 90 to mesh with the gear 91.

To raise a spindle rail by means of the above described mechanism the same procedure is followed as that described in connection with the mechanism described in Fig. 4 to the point where the spindle rails have been raised to their upper position. At this time the blank section 97 of the gear 91 is so positioned that the tooth 98 will have passed out of engagement with the thread of the worm but will continue to bear against the lower face 99 thereof to support the spindles in their raised position until the machine is adjusted again to start the spinning operation, at which time the hand lever 96 is thrown into the dotted position shown in Fig. 5 to disengage the worm 90 from the gear 91 and to permit the builder motion to again control the downward movement of the spindle rails.

Having thus described the invention, what is claimed as new, and desired to be secured by Letters Patent, is:

1. In a spinning frame, a plurality of spindles, a vertically movable spindle rail upon which the spindles are mounted, a builder motion acting to lower said spindle rail with said spindles and bobbins from its initial topmost position where the bobbins are empty down to full bobbin position and means detachably connected to a driven element of the machine acting when connected to lift the spindle rail with the full bobbins and spindles to its initial topmost position to permit doffing. 80

2. In a spinning frame, a plurality of spindles, a vertically movable spindle rail upon which the spindles are mounted, a builder motion acting to lower said spindle rail with said spindles and bobbins from its initial topmost position where the bobbins are empty down to the full bobbin position, and power driven means acting when connected to raise said spindle rail with the full bobbins and spindles back to its initial topmost position to permit doffing. 85

3. In a spinning frame, a plurality of spindles, a vertically movable spindle rail upon which the spindles are mounted, a fixed ring rail, a builder motion acting to lower the spindle rail from its initial topmost position where the bobbins are empty down to full bobbin position and means connectible to a driven element on the machine operable when connected to raise the spindle rail by power 100 into its initial topmost position to permit doffing and means acting automatically thereafter to disengage said spindle rail from said driven element. 95

4. In a spinning frame, a plurality of spindles, a vertically movable spindle rail upon which the spindles are mounted, a fixed ring rail, a builder motion acting to lower the spindle rail vertically relatively to the ring rail to lower the spindles from their initial topmost position when the bobbins are empty to full bobbin position and means manually connectible to a driven element on the machine acting when connected to lift the spindle rail by power into its initial topmost position to permit doffing. 110

5. In a spinning frame, a plurality of spindles, a movable spindle rail upon which the spindles are mounted, a fixed ring rail, a builder motion acting to lower the spindle rail vertically relatively to the ring rail from its initial topmost position when the bobbins are empty to full bobbin position, and means manually connectible to a driven element on the machine acting to lift the spindle rail carrying the spindles with full bobbins thereon by power into its initial topmost position to permit doffing and thereafter automatically to disengage from said driven element. 120

6. In a spinning frame, a plurality of 130

- spindles, a vertically movable spindle rail upon which the spindles are mounted, a fixed ring rail, a builder motion, a flexible connector acting to transmit the traverse and the gain of the builder motion to the spindle rail to lower it from its initial topmost position when the bobbins are empty to full bobbin position and means driven from a moving part of the machine connectible to said flexible connector acting to move the spindle rail carrying the spindles with full bobbins thereon by power into its initial topmost position to permit doffing.
7. In a spinning frame, a plurality of spindles, a vertically movable spindle rail upon which the spindles are mounted, a fixed ring rail, a builder motion, a flexible connector acting to transmit the traverse and the gain of the builder motion to the spindle rail to lower it from its initial topmost position when the bobbins are empty into full bobbin position and power driven means connectible to said flexible connector acting when connected to raise the spindle rail vertically into its initial topmost position to permit doffing.
8. In a spinning frame, a plurality of spindles, a movable spindle rail upon which the spindles are rotatably mounted, a fixed ring rail, a builder motion acting to move the spindle rail to carry the spindles axially through the rings in the ring rail from their initial position when the bobbins are empty to full bobbin position to permit doffing, means detachably connectible to a driven element on the machine acting to move the spindle rail by power into its initial position to permit doffing and thereafter to maintain such position of the rail as the driven element continues to move.
9. In a spinning frame, a plurality of spindles, a movable spindle rail upon which the spindles are mounted, a fixed ring rail, a builder motion acting to lower the spindle rail vertically relatively to the ring rail to lower the spindles from their initial position when the bobbins are empty to full bobbin position, means manually connectible to a driven element on the machine acting to lift the spindle rail by power into its initial position to permit doffing and thereafter to maintain such position of the spindle rail as the driven element continues to move and thereby prevent downward movement of the spindle rail before the builder motion is restored to starting condition.
10. In a spinning frame, a plurality of spindles, a movable spindle rail upon which the spindles are mounted, a fixed ring rail, a builder motion acting to lower the spindle rail vertically relatively to the ring rail to lower the spindles from their initial position when the bobbins are empty to full bobbin position, lifting means manually connectible to a driven element on the machine acting to lift the spindle rail by power into its initial position, means actuated by the builder motion to move the spindle rail vertically relatively to the ring rail to lower the spindles from their initial position when the bobbins are empty to full bobbin position and means actuated by the builder motion to move the spindle rail vertically relatively to the ring rail to raise the spindles from their initial position when the bobbins are empty to full bobbin position.
11. In a spinning frame, a plurality of spindles, vertically movable spindle rails upon which the spindles are mounted, fixed ring rails cooperating therewith, a builder motion acting to lower the spindle rails vertically relatively to the ring rails to lower the spindles from their initial topmost position when the bobbins are empty to full bobbin position, a transverse shaft rotatably mounted in the frame of the machine, flexible means connected from the ends of said transverse shaft to each spindle rail acting to raise the spindle rails when the shaft is rotated, means connected to a driven element on the machine manually connectible with and operable to rotate said transverse shaft whereby the spindle rails are raised by power into their initial topmost position.
12. In a spinning frame, a plurality of spindles, a movable spindle rail upon which the spindles are mounted, a fixed ring rail, a builder motion acting to lower the spindle rail vertically relatively to the ring rail from its initial position when the bobbins are empty to full bobbin position, a transverse shaft rotatably mounted in the frame of the machine, means connected thereto acting to raise the spindle rail when the shaft is rotated, means driven from a moving element on the machine, manually operable toggle means acting to connect said driven means with said transverse shaft to rotate the same whereby the spindle rail will be raised by power into its initial position.
13. In a spinning frame, a plurality of spindles, a movable spindle rail upon which the spindles are mounted, a fixed ring rail, a builder motion acting to lower the spindle rail vertically relatively to the ring rail from its initial position when the bobbins are empty to full bobbin position, a transverse shaft rotatably mounted in the frame of the machine, means connected thereto acting to raise the spindle rail when the shaft is rotated, a swinging bracket, an auxiliary shaft rotatably mounted therein and driven from a rotating element on the machine, a worm thereon, a worm gear adjacent said worm on said transverse shaft, manually operable means acting to swing said bracket to engage said worm and said gear whereby said transverse shaft may be rotated to lift the spindle rail and means acting automatically to disengage said worm and said gear when the spindle rail has reached the upper limit of its traverse.
14. In a spinning frame, a plurality of spindles, a movable spindle rail upon which

the spindles are mounted, a fixed ring rail, a builder motion, a flexible connector acting to transmit the traverse and the gain of the builder motion to the spindle rail to move it from its initial position when the bobbins are empty to full bobbin position, means driven from a moving part of the machine connectible to said flexible connector acting to move the spindle rail by power into its initial position to permit doffing and means acting automatically to disconnect said driven means from said flexible connector when the spindle rail reaches doffing position.

15 In testimony whereof, I have signed my name to this specification.

HENRY A. OWEN.
